UNITED STATES PATENT OFFICE.

EDWARD H. ELLISON, OF JAMESTOWN, NEW YORK.

WINDOW CLOSER.

Application filed July 25, 1924. Serial No. 728,262.

To all whom it may concern:

Be it known that I, EDWARD H. ELLISON, a citizen of the United States, residing at the city of Jamestown, in the county of Chautauqua and State of New York, have invented certain new and useful Improvements in a Window Closer, of which the following, taken in connection with the accompanying drawings, is a specification.

10 This application relates to an improvement in a window closer, and more particularly in an automatically acting closer for windows of the casement type.

One difficulty that has arisen in casement windows is that the free corners, i. e., those on the edge furthest from that bearing the hinges, are not always brought into the proper position in the casing, due to warping or unevenness in the window frame.

20 The primary object of this invention is to provide a closer consisting of two elements, one of which is mounted upon the window and the other upon the casing, one of said elements including movable parts and the 25 other including fixed parts, the said elements being so constructed that upon the shutting of the window they will automatically engage to close it tightly, and, in case there be any warping or unevenness in the window, 30 overcome any tendency not to close securely, and will automatically be released from engagement when the window is opened.

A further object of this invention is to 35 provide a closer comprising a movable and a fixed element, the movable element including a finger and a lever connected by a rod, and the fixed member including a trip, with which the lever engages and a pin with which the finger is forced into contact by 40 the engagement of the trip and lever to close the window.

Other objects of this invention will appear from the following description taken 45 in connection with the drawings which form a part thereof, and in which

Fig. 1 is a front elevation of a casement window provided with one embodiment of this invention;

Fig. 2 is a sectional view taken along the 50 line 2—2 of Fig. 1;

Fig. 3 is a view similar to Fig. 2 showing the parts in the open position;

Fig. 4 is an enlarged view partly in section of the top and bottom portions of the 55 movable element in the closed position;

Fig. 5 is a sectional view of the upper portion of this element in the open position;

Fig. 6 is a front elevation of a second embodiment of this invention;

Fig. 7 is a side elevation of this embodiment;

Fig. 8 is a sectional view taken along the line 8—8 of Fig. 6;

Fig. 9 is a sectional plan view on a smaller scale taken along the line 9—9 of Fig. 7;

Fig. 10 is a similar view taken along the line 10—10 of Fig. 7;

Fig. 11 is a view on a small scale similar to Fig. 7 illustrating the position of the parts when the window is partially opened;

Fig. 12 is a front elevation of a third embodiment of this invention;

Fig. 13 is a side elevation;

Fig. 14 is a side elevation similar to Fig. 13, showing the parts out of engagement;

Fig. 15 is a plan view taken in the direction of the arrow 15 on Fig. 12;

Fig. 16 is a view taken along the line 16—16 of Fig. 12 of the movable element only; and

Fig. 17 is a view taken along the line 17—17 of Fig. 13.

Referring to Figs. 1 to 5 of the drawings, the reference numeral 20 is employed to designate a casing in which is mounted a casement window 21. The window and casing are illustrated in Figs. 1, 2 and 3 as of wood, although it is not essential that they be so constructed.

22 is employed to designate a controller 90 for casement windows which I have shown of the type set forth in my co-pending application, Serial No. 722,477, filed June 26th, 1924, but it will be understood that the particular type employed is no part of my present invention, and that any type may be used or the window may be closed or opened manually.

Mounted upon the frame of the window 21 is an element A, which consists of a finger 24, and a lever 25 connected by a rod 26, and which will hereafter be referred to as the movable element. The finger 24 is pivotally mounted upon a bracket 27, which is carried by the frame of the window 21 adjacent the upper edge and the lever 25 is pivotally mounted upon a bracket 28, which is carried by the frame adjacent its lower edge. The finger 24 normally projects substantially horizontally, as shown in Fig. 5,

being held in that position by means of a spring 29 which is preferably enclosed within the bracket 27. When so positioned the lever 25, because of its connection through the rod 26 with the finger 24, projects below the bracket 28, as suggested for example in Fig. 3.

Rigidly mounted upon the frame of the window is a fixed element B, which consists of an upper member 31 and a lower member 32. Projecting from the upper member 31 is a pin 33, which as shown in Fig. 2 is clamped by the finger 24 when the parts are closed. The member 32 functions as a trip and has an inclined face 34, with which the lever 25 engages when the window is shut, as will be pointed out. In order to eliminate as much friction as possible, there is mounted on the outer end of the lever 25 a roller 35, which bears against the face 34 of the trip 32.

The face 34 of the trip 32 is preferably made up of two inclines 36, 37 at different angles, the incline 37 being much more abrupt than the incline 36, and the lower face of the bracket 28 is inclined similarly to the portion 36 of the face 34, so that, when the window is closed, as shown particularly in Figs. 2 and 4, the bracket will rest upon the incline 36. The length of the incline 37 is such that when the window is completely closed, the roller 35 will pass beyond this incline and rest against a reverse incline 38. The rod 26 connecting the finger 24 within the lever 25 is preferably adjustable, a union 39 being shown as indicating one manner of attaining this result.

When the window 21 is closed, the element A is brought up to the element B, the lever 25 engaging the trip 32 and resting first against the incline 36 and through the rod 26 raising the outer end of the finger 24 slightly, and then as the window is closed further, the roller 35 climbing the incline to raise the finger 24 into the vertical position against the pin 33, thus forcing the upper corner of the window into its proper place in the casing. From this description, it will be apparent that in case there be any unevenness in the window frame due to the warping or other causes which would normally prevent the complete closing of the upper corner of the window, this will be overcome and the window forced into the completely closed position, as illustrated in Fig. 2.

Since, as pointed out above, the roller passes beyond the top of the incline 37, there will be a slight relaxation of the pressure of the finger 24 against the pin 33 when the parts are in the final position. This is however, a very slight relaxation and has no effect upon the closing of the window. It does, however, insure the complete closing of the lower corner under the influence

of the spring 29, which tends to force the roller 35 to descend along the incline 38 and draw the lower corner into place. Moreover, if the outer portion of the window has sagged a trifle, the angular contact of the lower face of the bracket 28 with the incline 36 will force the window frame upwardly so that it will be completely closed.

Moreover, since as will appear from Fig. 4, the axis of the roller 35 is beyond the line separating the inclines 37 and 38 any attempt to break in by forcing the window open will cause the roller 35 to move down the incline 38 and thus clamp the bottom more securely. On the finger 24 is formed a lug 30 which rests below the pin 33 and which prevents any attempt to break in by forcing the window open by raising it from below.

Upon the opening of the window the lever 25 and trip 32 permit the spring 29 to act, drawing the rod 26 upwardly and at the same time the pin 33 causes the finger 24 to turn on its pivot, thus supplementing the action of the spring and insuring the separation of the elements regardless of the action of the spring.

When a closer of this type is installed upon casement windows made of metal, it has been found desirable to reverse the arrangement previously described, and to mount the movable element A upon the window casing and the fixed element B upon the window frame. This rearrangement of parts is shown in Figs. 6 to 17 inclusive, in which two embodiments are illustrated, but it is apparent that the elements A and B in these embodiments cofunction in the same manner as they do in the embodiment previously described.

Referring first to the embodiment shown in Figs. 6 to 11 inclusive, the movable element A, as stated above is mounted upon the casing 40 and the fixed element B is mounted upon the frame 41 of the casement window. The movable element A comprises the finger 42, the lever 43 and the connecting rod 44. The rod 44, which is adjustable in length by means of a union 45, connected to arms 46, 47 which are in turn connected with the finger 42 and lever 43, as will be pointed out below, and is normally held in the raised position by means of a spring 48 enclosed within a bracket 49 which carries the finger 42. The bracket 49 has outwardly projecting cheeks 50, between which one end of the arm 46 extends. From the finger 42 projects a shank 51, which is cylindrical at 52 where it passes through one of the cheeks 50 and is squared at 53 where it extends into the similarly shaped opening 54 in the arm 46. The outer end 55 of the shank 51 extends beyond the arm 53 through the other cheek 50, that portion 55 being cylindrical and preferably peened over as indicated in Fig. 6. A certain amount of play is pro-

vided in the mounting of the finger 42 for a purpose to be described later.

The lever 43 is mounted upon a bracket 56 which is provided with outwardly projecting cheeks 57, between which one end of the arm extends. The shank 58 is similar in form to the shank 51 of the finger 42, having a cylindrical portion 59 which passes through one cheek 57, a squared portion 60, which passes through a similarly shaped aperture 61 in the arm 47 and a cylindrical trip 62 which passes through the other cheek 57, the outer end being peened over as stated above. In the mounting of this lever also there is provided a certain amount of play.

The fixed element B of this embodiment comprises an upper member 63 mounted upon the frame of the window provided with an outwardly projecting pin 64, the tip 65 of which is bent at right angles thereto into the horizontal plane, and a lower member or trip 66 also mounted on the frame and provided with a vertically projecting flange 67. When the window 41 is open, the parts of the movable element A take the normal position shown in Fig. 11 under the influence of the spring 48. Upon the closing of the window 41, the elements A and B are brought together, the flange 67 of the trip 66 striking the nose of the lever 43 and causing it to turn in the cheeks 57 and pull the rod 44 downwardly. This movement of the rod 44 swings the finger 42 inwardly into engagement with the tip 65 of the pin 64 and thus forces the window frame into its closed position in the casing 40. See Fig. 7.

Upon the finger 42 is formed a lug 68 which, when the window is closed projects above the tip 65 of the pin 64 and checks any attempt to force an entry by raising the window and in case the window is uneven, forces it downwardly into approximately the proper position. When the window is opened the trip 66 moves away from the lever 43, permitting the spring 48 to function, and at the same time the tip 65 pulls against the finger 42, thus supplementing the action of the spring and insuring the separation of the elements A and B, should the spring be broken or weakened.

The embodiment shown in Figs. 12 to 17 inclusive illustrates an arrangement of elements similar in function to that previously described. This embodiment is also particularly intended for installation upon metal casement windows, although it could be used on other windows if desired. The movable element A is mounted upon the casing 70 and the fixed element B is mounted upon the window frame 71. The movable element A in this embodiment comprises as in the other instances a finger 72, and a lever 73 connected by a rod 74, which is normally held in the inoperative position under the influence of a spring 75. The finger 72 is piv-

otally mounted upon a bracket 76, which encloses the spring 75 and the lever 73 is mounted upon a bracket 77, these brackets being rigidly secured upon the casing 70 in any suitable manner.

The fixed element B comprises a pin 78 which is mounted upon the frame of the window and which projects outwardly and forwardly as indicated particularly in Fig. 15, and a trip 79, the projecting face 80 of which is inclined as shown in Figs. 13 and 14. When the window 71 is closed by any suitable means bringing the elements A and B together, the lever 73 strikes the inclined face 80 of the trip 79 and is raised into the position shown in Figs. 12 and 13. This movement of the lever 73 pulls the rod 74 downwardly and raises the finger 72, which engages the underside of the pin 78 and by reason of the formation of the latter, forces the window into the closed position. Upon opening the window, the lever 73 slides down the inclined face of the trip 79, permitting the spring 75, while the separation of the finger 72 and pin 78 forces the finger to turn on its pivot and supplements the action of the spring thus insuring the separation of the elements upon the opening of the window regardless of the spring 75.

In each of the embodiments here shown and described the distance from the pivot of both finger and lever from the connection with the rod is the same, thus providing a parallelogram of forces and insuring the proper movement of both finger and lever. The length of the finger beyond the pivot is, however, greater than that length of the lever and thus the end travels through a greater arc. The advantage of this fact is that in case the upper free corner is warped outwardly, it will still be drawn into proper position in the casing so long as the finger can engage the pin and draw the window into place.

While certain embodiments of this invention have been shown and described, applicant is not limited thereto, since it is obvious that other embodiments can be made without departing from the spirit and scope of this invention as set forth in the following claims.

Having thus set forth my invention what I claim as new and for which I desire protection by Letters Patent is:

1. A closer for casement windows comprising a movable element, and a fixed element, one of said elements mounted upon the window casing and the other mounted upon the frame of the window, whereby upon the shutting of the window they are brought into engagement and automatically draw the free corners of the window into the casing, thus eliminating any gap that might result from any unevenness in the window frame.

2. A closer for casement windows comprising a movable element, including a pivotally mounted finger, and a fixed element including a pin, one of said elements mounted upon the window casing and the other mounted upon the frame of the window, said elements being so formed and located that upon the shutting of the window they are brought into engagement and said finger and pin automatically co-acting to draw one of the free corners of the window into the casing thus eliminating any gap that might result from any unevenness in the window frame.
- 6 10 15 20 25 30 35 40 45 50 55 60 65 70 75 80 85 90 95 100 105 110 115
6. A closer for casement windows comprising two elements, one mounted upon the window casing and the other mounted upon the frame of the window, one of said elements including a pivotally mounted finger and a lever connected by a rod, and the other element including a pin and a trip so located that when the window is closed the trip will engage the lever and through the rod force the finger into contact with the pin to draw the window fully closed.
7. A closer for casement windows comprising two elements, one mounted upon the window casing and the other mounted upon the frame of the window, one of said elements including a pivotally mounted finger, a lever connected by a rod and a spring for normally holding said finger and lever in a certain position, and the other element including a pin and a trip so located that when the window is closed the trip will engage the lever and through the rod force the finger against the tension of said spring into contact with the pin to draw the window fully closed.
8. A closer for casement windows comprising a movable element and a fixed element, one of said elements being mounted upon the window casing and the other being mounted upon the frame of the window, said elements being so formed and located that upon the shutting of the window they will automatically function to draw one free corner of the window into proper position and upon the opening of the window the elements will be automatically released.
9. A closer for casement windows comprising a movable element mounted upon the frame of the window and a fixed element mounted upon the window casing, said movable element comprising a finger pivotally mounted upon a bracket, adjacent the upper portion of the frame, a lever mounted upon a bracket adjacent the lower portion of the frame, and a rod connecting said finger and lever, and said fixed element comprising a pin mounted adjacent the upper portion of the casing and a trip mounted adjacent the lower portion of the casing, said parts being so located that upon shutting the window the lever engages the trip pulling the rod downward and raising the finger beyond the pin into contact therewith whereby pressure is exerted against the pin and the upper free corner of the window is drawn into its place.
- 10 15 20 25 30 35 40 45 50 55 60 65 70 75 80 85 90 95 100 105 110 115
7. A closer for casement windows comprising a movable element mounted upon the frame of the window and a fixed element mounted upon the window casing, said movable element comprising a finger pivotally mounted upon a bracket adjacent the upper portion of the frame, a lever mounted upon a bracket adjacent the lower portion of the frame, the lower face of said bracket being upwardly and outwardly inclined, and a rod connecting said finger and lever, and said fixed element comprising a pin mounted adjacent the upper portion of the casing and a trip mounted adjacent the lower portion of said casing, the upper face of the trip being upwardly and outwardly inclined, said parts being so located that upon shutting the window the lever engages the upper face of said trip, pulling the rod downward and raising the finger beyond the pin into contact therewith, the lower face of the lever carrying bracket resting upon the upper face of the trip whereby the window is squared into the casement window and the upper free corner is drawn into its place.
8. A closer for casement windows comprising a fixed element mounted upon the frame of the window and a movable element mounted upon the window casing, said fixed element comprising a pin projecting outwardly mounted adjacent the upper portion of the frame, and a trip projecting outwardly mounted adjacent the lower portion of the frame, and said movable element comprising a finger pivotally mounted upon a bracket adjacent the upper portion of the casing, a lever mounted upon a bracket adjacent the lower portion of the casing, and means connecting said finger and lever and insuring corresponding movement thereof, said parts being so located that upon shutting the window the lever is engaged by the trip and swung on its pivot drawing down the rod and raising the finger between the pin and the window frame into contact with the pin, thereby drawing the free corner of the window into its place in the casing.
9. In testimony whereof I have affixed my signature.
- EDWARD H. ELLISON.
